FOLDING NEWSPAPER AND SALES BENCH

Henry J. Bocker, Bronx, N. Y.

Application April 12, 1937, Serial No. 136,374

2 Claims. (Cl. 211—149)

This invention relates to an improved foldable display bench, and its leading object is to provide a bench which can be used for selling newspapers, and which when in upright position will provide a 5 table surface on which newspapers or magazines may be displayed, or other merchandise arranged for display, and which may be folded so that all parts will lie flat against each other.

With the above and other objects in view the 10 invention relates to certain new and useful constructions, combinations, and relations of parts, clearly described in the following specification, and fully illustrated in the drawing, in which:—

Fig. 1 is a front elevation of the improved 15 folding bench, shown in an upright condition.

Fig. 2 is an end view thereof, partly broken away, for convenience of illustration.

Fig. 3 is a detail view of the rear corner portion 20 of the bench, showing the manner in which the leg is locked in open position.

Fig. 4 is an edge view, showing the complete bench folded.

Referring to the drawing illustrating my invention, 5 designates the top or horizontal table member of the bench. This member is equipped 25 on its opposite ends with cross cleats or reinforcing bars 6 and 7, shown in Fig. 4.

The cleats or bars 6 and 7 are hingedly connected at 8 to the end cleats or bars 9 of the 30 front vertical member or board 10, these cleats or bars being secured to the ends of the board 10.

The vertical front member or board 10 is secured in upright position at approximately right angles to the board or table member 5, by means 35 of the folding flat board legs 11 and 12. The leg 11, shown in Fig. 3, is hinged to the inside of the vertical board 10, by the hinges 11a, so that the leg will abut against the inner edges of the adjacent cleats or bars 6 and 9, and bear against the inner surface or side of the horizontal board 40 5. The legs 11 and 12 are provided with cleats or reinforcing bars 13, which carry the hinge leaves attached to the legs.

The legs are retained in open positions, by 45 means of the spring retainers 14, which are fixed to the inner side of the top board 5, and adapted to latch the legs in place, when the legs are shifted to open position.

The legs cannot then accidentally fold under 50 the top member, and the weight of any newspapers, magazine or other articles upon the top member tends to hold the legs in upright open positions.

The leg member may project below the lower edge of the vertical front board, or may be level with the lower edge of the vertical front board.

When the bench is folded the legs will fit in the compartment or space between the inner sides 5 of the top board 5 and the vertical board 10, as the combined thickness of the legs and their hinges will be less than the combined thickness of the paired cleats or bars on each end of the bench. These legs also support the intermediate 10 portions of the boards 5 and 10, when the bench is folded, so that the boards 5 and 10 will not be broken, when a number of benches are stacked or piled on each other, or loaded with merchandise.

A folding magazine rack board 15 is hinged to 15 the rear top edge of the table board 5, so as to fold forwardly against the top board. This magazine and newspaper display board is provided at its ends with cleats or bars 16 and 17, located at the ends thereof, to which the connecting 20 18 and 19 are secured. Supporting bars or ledges 20 and 21 are provided on this board 15, being located one above the other.

Retaining wires 22 and 23 are arranged on this board 15, the ends of which are secured to the bars 25 16 and 17. In some constructions this folding magazine board may be omitted. This board can be folded on the bench, even if magazines or newspapers, or other articles, are arranged on the ledges thereof.

Having described my invention I claim:—

1. A folding sales bench, consisting of a top board having bars on each end thereof on one side of the board, a vertical front board having bars on each end thereof also on one side thereof, 35 said vertical board being hinged to the top board so that the end bars of the vertical board will fold directly over and against the end bars of the top board when the bench is collapsed, and leg board members hinged to the inner side of the vertical board adjacent the end bars of the latter and adapted to fold in open position against the end bars of both boards.

2. The construction set forth in claim 1, including a folding board hinged to the top board 45 and adapted to fold against the same, and provided with longitudinal ledges and wires for retaining objects on the ledges and provided with end bars which engage the top board, whereby said folding board may be folded against the top 50 board when loaded with flat objects.

HENRY J. BOCKER.
